ORE CRUSHER

Robert Linn, Chicago, Ill.; Lawrence W. Whitmer, administrator of said Robert Linn, deceased, assignor, by mesne assignments, to Eureka Machinery Company (Limited) Trust Estate, Chicago, Ill.

Application January 14, 1933, Serial No. 651,721

16 Claims. (Cl. 83—53)

The purpose of this invention is to provide an apparatus for crushing refractory material, such as mineral ores and slag, or natural rock suitable for making cement, which shall be more efficient for the purpose than structures hitherto commonly employed, both in respect to the degree and uniformity of fineness of the product, and in respect to the rate at which the product can be produced with an apparatus of given size, and 10 operated by given horse power; and which shall be more economical in construction and adapted for longer and more severe service with less wear than the structures in common use.

The invention consists in the elements and features of construction shown and described as indicated in the claims.

In the drawings:

Figure 1 is a top plan view of a machine embodying this invention.

Figure 2 is a horizontal vertical section at the line 2—2 on Figure 1.

Figure 3 is a transverse section at the line 3—3 on Figure 1 on somewhat larger scale than Figure 1.

Figure 4 is a front side elevation of the structure shown in Figure 1.

Figure 5 is an enlargement of a portion of the sectional view shown in Figure 2 showing the crushing jaws and intervening rotor with 30 which they cooperate for crushing or grinding.

Figure 6 is an inner face view of one of the crushing jaws.

Figure 7 is a side elevation of the rotor, its shaft being shown in section.

Figure 8 is a perspective view of a part which is concerned in the operating of toggles by which the jaws are given their crushing movement.

Figure 9 is a front side elevation, partly in section, of a modified form of the structure shown 40 in Figure 1.

Referring to the drawings:—The apparatus illustrated comprises a pair of crushing jaws, 20, 20, identical in form and operation, which are mounted facing each other, as hereinafter more particularly described, each in one of the adjustable parts, A¹, of the frame structure indicated as to its entirety at A, and which are actuated for their crushing movement by toggles, 30, arranged in pairs at opposite sides of the pair of jaws, as seen most clearly in Figures 1 and 2, each toggle being connected at the inner end, as seen at 21, to the jaw which is to be actuated at the outer side thereof, and at the outer end, 50 as seen at 22, to an upright member, a¹, of the

adjustable frame member, A¹, located at said outer side of the jaw.

The two toggles of each pair are connected to the jaws which they operate, one near the upper end and the other near the lower end of the jaws, as seen at 24, and the ends of the toggles are connected at corresponding higher and lower positions on the uprights, a¹, of the adjustable frame member, A¹.

The crushing jaws, 20, 20, are pivotally mounted respectively on the adjustable frame members, A¹, for oscillating each about a horizontal pivot located midway in the vertical extent of the cooperating faces of the jaws, the jaws being for such mounting formed with bosses, 25, projecting transversely toward the opposite longitudinal side bars, a², formed with corresponding bosses, 26, between which the jaws, including their bosses, 25, are dimensioned for close fit, and the mated bosses of the jaw and frame bar are bored to receive pivots, 27, dimensioned for drive fit in the bores of the jaw bosses and for rocking fit in the bores of the frame bar bosses, beyond which latter the pivots project to receive stop collars, 28, secured to the pivots by key pins, as indicated at 28^a.

The frame members, A¹, are each independently mounted slidingly on the base web, A³, of the frame, A, which is formed with longitudinally extending side flanges, a⁴, between which a bottom web, a⁵, of the adjustable frame member which is fitted, as seen at a⁶ in Figure 3, and retained against vertical displacement by retaining bars, A⁴, bolted to the flanges, a⁴, as seen at a⁷.

For adjusting the adjustable frame member longitudinally of the main frame for operably spacing apart the jaws there is provided on each of the end uprights, A⁶, of the main frame adjustable means consisting of a horizontal adjusting shaft, 30, journaled on the outer side of the upright, A⁶, extending across the entire width of the frame and projecting at both ends beyond its journal bearings, 31, and carrying outside said journal bearings at each end an eccentric, 32, which may be referred to as a crank wrist; and at which side of the adjustable frame member,—at each end of the adjusting shaft, 30,—there is provided a connector, 35, which may be referred to as a pitman engaged at one end by suitably dimensioned ring terminal, 35^a, with the eccentric or crank wrist, 32, and at the other end engaged with a pivot stud, 33, on the outer side of the lateral longitudinally extending web, a⁷, of the adjustable frame member.

The ends of the shaft, 30, are formed, as seen 55

at 30^a, to receive a suitably formed operating crank (not shown) for rotating the shaft to operate the pitman for adjusting the adjustable frame member; and the bearings, 31, of the shaft, 5 30, are each split and furnished with a clamping bolt, as seen at 33 for clamping this shaft securely in the bearings for holding the adjustable frame in adjusted position.

From the foregoing description it may be recognized that the function of the toggles, 30, connecting the opposite crushing jaws respectively to the opposite end uprights of the sliding frame member, A¹, respectively, is to oscillate the jaws each about its horizontal pivot, which may be effected as to each jaw by the alternating straightening and flexure of the toggles which are connected respectively to the jaw above and below the pivot; and that if means is provided for straightening each toggle of the pair concurrently with the flexing of the other toggle of the pair, and as to the two sets of toggle connections, connected respectively with the opposite jaws, for producing the straightening movements of the upper toggles of the two sets simultaneously, and likewise producing the straightening movement of the lower toggles of the two sets simultaneously, the jaws will be oscillated oppositely for alternately closing and opening the gap at their upper ends and simultaneously 10 15 20 25 30 35 40 45 opening and closing the gap at their lower ends. And it will be understood that the purpose accomplished by such alternate opening and closing movements at the upper and lower sides of the oscillating jaws,—which closing movement in both instances, viz., at the upper and lower sides,—is effected by the straightening of the toggle producing thrust with maximum leverage,—which is the mechanical characteristic of a toggle,—on the jaw at a substantial distance from its pivot and thereby with advantage of additional leverage for crushing the material which will have descended toward the pivot of the jaws while they have been opening at the upper side, so that a very powerful crushing effect is obtained while the jaws are opening at the lower side for free delivery of the crushed material.

For operating the toggles for producing the thrust for closing the jaws together alternately at the upper and lower sides,—above and below 50 55 60 the fulcrum of the jaw considered as a lever of the first class having equal arms,—there is provided a shaft, 50,—power-driven, as indicated by the band wheel or fly wheel, 51,—said shaft journalled in the end upright A⁶, of the main frame, A, as seen at 52, and also in the upright, a¹, of each of the sliding frame members, A¹, as seen at 53, 53, and having additional journal bearing seen at 54, 54, in the posts, a⁵, a⁵, with which the sliding frame members are provided, as seen in Figure 2.

The shaft, 50, carries in the zone of the knee joints of each pair of toggles an eccentric cam member, 70, which may be referred to as a crank wrist, and which is mounted between the journal 65 70 75 bearings, 53, and 54 and engaged with said journal bearings for sliding vertically there is provided a part, 71, having a horizontally elongated aperture, 72, whose width vertically is the diameter of the eccentric cam or crank wrist, 70, and in which aperture said cam crank wrist is engaged for reciprocating said part, 71, vertically in its said slide bearings in the rotation of the shaft. Said part, 71, is connected at its opposite ends by links, 73, 73, with the knee joint pivot, 75 30^x, of the upper toggle, 30, and by links, 74,

74, with the knee joint pivot, 30^y, of the lower toggle, 30.

The above description applies to the construction of both sides of the jaw assembly which operates the actuating the jaws the parts mentioned, identical at both sides of the jaw assembly, being identified by the same reference characters.

The operation of this eccentric cam or crank wrist and cooperating connections with the toggle knee joints, which connection may be referred to as crank-and-pitman, will be obvious from the construction without further description.

For cooperation with the crushing jaws for their crushing function, there is provided, mounted on the shaft, 50, for rotation therewith, between the two jaws a rotor, E. This rotor is in general of diamond shape in diametric section with hubs, E¹, E¹, by which it is mounted on the shaft, 50, and keyed thereto as indicated by the key seen at e.

The acute angle of the diamond form of the rotor is such as to make the slope of the outer surfaces correspond with the depth of the recesses of the opposed faces of the jaws; and in the construction as illustrated these recesses being spherical in form,—conformed to a segment of a sphere,—the slope of the diamond form of the rotor is that of a chord of the arc of the spherical form of the recesses, as seen in Figures 1 and 5.

For lodgment and engagement of the fragments of material to be crushed as they enter the space between the jaws and the rotor, the rotor is formed on its opposite faces with shallow recesses or pockets, 75, seen most clearly in Figure 35 7, sectoral in general outline and uniformly spaced apart circumferentially at intervals, measured at the circumference of the rotor, approximately equal to the arcuate extent of the pockets at said circumference. But this dimensional relation is not essential.

Upon considering the construction including the rotor mounted between the crushing jaws, it will be evident that the capacity of the apparatus for crushing to reduce the crushed material to relatively small fragments or crumbs, is at least doubled by the addition of the rotor, independently of the rotation of the latter; since as much crushing will be effected between either jaw and the rotor as would be effected between the two jaws in the absence of the rotor, assuming the jaws in the absence of a rotor to be formed for spacing their opposed surfaces as closely and as widely apart as the faces of the rotor and jaws are spaced in the construction shown. And it will be seen that this double capacity for fragmentizing or reducing to crumbs is further greatly increased by the rotation of the rotor engaging by the recesses or pockets, 75, any ore fragments which are larger in some dimension than the spacing of the jaws from the rotor at the upper side of the shaft while the jaws from the rotor are being rocked for widening the gap at the upper side, the ledged fragments being carried around to the lower side while the jaws are closing for crushing the material thus carried between them, while at the same time additional material is taking its place at the upper side vacated by the material thus carried around, whereas if the rotor were not being rotated, the fragments first caught and stopped between the jaw and the rotor at the upper side would be held in that position, delaying the delivery of additional material while the jaws completed their rocking movement for closing together at the upper side.

and crushing the material there engaged so that it would fall and be discharged through the jaws widely opened at the lower side. From this construction it may be calculated, first, that the 5 interposition of the rotor between the jaws doubles the crushing capacity of the apparatus, and second that the rotation of the rotor again doubles said capacity, so that the presence and rotation of the rotor at least quadruples the 10 crushing capacity of the apparatus over what it would be with the two jaws operating as described without the intervening rotor.

For full understanding of the operation of the apparatus in the crushing process, and noting the 15 reasons for the detail form of the cooperating elements, let it be assumed that a piece of refractory material which is exposed to the crushing action is a substantially rectangular oblong block which has resulted from the initial crushing of a 20 larger block between the flaring entrance flanges at the upper ends of the jaws. Upon this assumption it will be seen that such block having in the opening movement of the jaws at their upper ends passed into the gap between the conically concave face of the rotor, and the spherically concave face of one of the jaws, will in the ensuing 25 closing movement of the jaws be encountered at opposite ends by the spherically concave face of the jaw, and will encounter at the middle point of its length the conically convex face of the 30 rotor, and will thus be subjected to a stress tending to break it at what may be thought of as its fulcrum point, viz., the point of encounter with the convex face of the rotor; and that it will be broken at that point by a small fraction of the 35 force which would be necessary to crush it if its encounter with the rotor and jaw occurred at directly opposite points, as for example, the surfaces between which it was grasped were both flat 40 faces, which would make the stroke of the jaw upon the ore fragment like the blow of a hammer upon such fragment resting upon an anvil. And although of course the ore fragments entering the jaws for being crushed will not be symmetrical 45 blocks as assumed, the condition in respect to the grasp of the cooperating jaws and rotor faces upon the irregular pieces of ore which enter between them in the opening movement of the jaws approximating those above described in respect 50 to a symmetrical block. And thus it may be understood that each blow or bite of the jaws upon the ore fragments reaching them is multiplied in effectiveness for breaking the same into smaller fragments by the form of the cooperating faces of 55 the rotor and jaw respectively resulting in the advantageous leverage described.

And upon further consideration it will be seen that due to the spherical form of the concavity of the jaw, the block will be encountered not only 60 at opposite sides horizontally of the point of lodgment of the block against the conically convex face of the rotor, but also at opposite sides vertically of such point of lodgment, at least if the block is to any extent protruded toward the rotor at the point of its lodgment; so that the opening 65 and breaking stress of the crushing stroke of the jaw will operate for breaking the block in both horizontal and vertical directions, resulting in bending and breaking the block into at least four 70 fragments instead of only two, as will result from the action if the jaw face were conically or cylindrically instead of spherically concave.

The main frame bottom web, A³, is formed with an aperture seen at a¹⁰, directly below the jaw 75 assembly for admitting the crushed material de-

livered from between the jaws at their lower side to a suitable receptacle or storage room (not shown) which may be understood to be located in or below the foundation support indicated at H on which the apparatus in entirety is mounted, 5 as seen in Figure 1. And above the crushing apparatus there is provided a chute as indicated at N, leading from a source (not shown) of material to be crushed, said chute terminating for discharge directly over the funnel mouth of the 10 crusher which is formed, as described by the two flaring flanges, 20^a and 20^b, of the jaw members. Said chute may be referred to as means for introducing material to be crushed between the 15 crushing jaws.

Upon considering the operation of the jaws for crushing, and the utilization of toggles for obtaining the advantage of leverage which is the characteristic of the toggle, and further noting that of the material to be crushed delivered from 20 the chute, N, into the funnel mouth of the crushing jaws, the larger fragments are liable to be prevented by their size from passing what may be called the throat of the funnel, even at the position of widest opening of that throat, that is, 25 when the jaws are rocked in the direction due to straightening of the lower toggle and the folding of the upper toggle, and that these larger fragments will accordingly experience the crushing action of the jaws when the toggle action is 30 reversed, that is, the upper toggle being straightened and the lower toggle flexed, it will be noted that for crushing the fragments thus detained, the upper ends or sides of the jaws most remote 35 from the fulcrums of the levers which the jaws 40 constitute, the maximum leverage value of the toggles should desirably be made available; and it may be recognized that this desirability will be attained only by locating the toggles which 45 actuate the jaws at the upper end, for connection 50 with the jaws as nearly as possible at the upper ends of the latter. Accordingly, in the construction shown in Figure 9, both jaws are shown connected at their upper ends with the adjustable frame uprights, a, by toggles, 300, 300, said toggles having their knee joint pivots, 300^a, connected by links, 300^b, with the knee joint pivots of the upper toggles, 30. In this construction the 55 excess of range of oscillation of the pivots, 300^a, of the toggles, 300^b, connecting said toggles to the upper end of the jaw over that of the pivots of the upper toggles, 30, to the jaw, said excess due to the greater distance of the first mentioned pivots from the fulcrum of the jaw, is compensated or accommodated by making the outer toggle 60 member, 30, in the form of a bell crank lever with the lever arm, 30^w, carrying the pivot for connecting the corresponding toggle member, 300, instead of pivoting said toggle member, 30, directly to the frame upright, a¹.

It will be understood that an apparatus of the construction described when designed for crushing the refractory material mentioned,—mineral slag or hard natural rock,—will have the jaws and rotor made of correspondingly hard and 65 tough material, the jaws being desirably made of manganese steel casting, and the rotor of the same or any equally tough and hard metal.

In the operation of such machinery there is liability to accident from pieces of casting or 70 hard metal tools, such as a sledge hammer or monkey wrench being dropped into the hopper or container from which the partly fragmentized ore is delivered by the chute, N, to the crusher jaws; and thus being delivered into the latter to be 75

caught between the jaws through which it is too large to pass, and too hard to be crushed, and being thus caught, for example, in the funnel mouth and engaged by the teeth in the closing movement of the upper end of the jaws, preventing the completion of the closing movement and stopping the operation of the machine. Or it may happen that being of such size that it can pass the funnel throat and enter between the rotor and either jaw in the closing movement of the jaws at the upper end, and being engaged in the pockets of the rotor, it will at least blockade the machine, preventing the passage of the material to be crushed.

Upon the occurrence of such accidents, it will be necessary to stop the machine and in some manner extricate the accident-causing article. And this is facilitated and made possible without disassembling the machine by the provision above described for adjusting the sliding frame members, A¹, the range of adjustment provided by the diameter of the eccentric cam or crank wrist, 31, and the range of sliding movement of the frame members, A¹, in the main frame being such as to permit the separation of the jaws farther than the dimension of any article which could enter the funnel mouth.

In practical operation of a machine of this character of proper size for handling mineral ore for the purpose of crushing to crumb size suitable for passing through a grinder or pulverizer for reducing it to a flour, the normal speed of the driving shaft is about 300 revolutions per minute, and both jaws being oscillated back and forth in each revolution, four hammer blows are delivered upon the material to be crushed in each revolution of the shaft, making 1200 blows per minute, or 20 per second. These blows being delivered with the almost infinite leverage of the toggle supplemented by the leverage due to the distance from the jaw fulcrums to the point at which the toggles are connected, the pressure for crushing the material which has dropped toward and arrived nearly at the line of the fulcrum is sufficient to crush the hardest ore, natural rock or slag. Any fragments less in all dimensions than the distance at which the jaws are spaced from the rotor at the hub of the latter, will pass through the jaws by gravity, leaving the larger fragments to be delivered without delay as far down in the funnel mouth and between the jaws and the rotor as their dimension will permit. The pockets or recesses, 75, which have the function, first, of catching the finer material and flinging it off centrifugally, and second of arresting and holding the larger fragments where they can be crushed lodged in said recesses on the lower shoulder thereof during the opening movement of the jaws at the upper side until the reverse movement occurs for crushing the material thus lodged, are desirably not over one-eighth of an inch deep, spacing the bottom surface of the recess not more than one-fourth of an inch from the opposite under face of the adjacent jaw; and a machine of this character of average size is dimensioned otherwise than as to depth for containing in each recess or pocket about six pounds of ordinary mineral ore, when reduced to crumbs of one-fourth of an inch and finer, which in view of the limited depth of one-eighth of an inch will be the result of each crushing action due to the closing of the jaws at the upper side. The capacity of the machine for delivery of material crushed to one-fourth of an inch or finer computed on this basis, is six pounds per pocket, eight pockets each side

of the rotor making ninety six pounds for each revolution of the rotor, revolving, as indicated, at the rate of three hundred revolutions per minute, making nearly twenty tons per hour. It may be computed that the power of each blow or crushing movement of either jaw is approximately one million foot pounds; and upon consideration of the operation it will be seen that if the average time occupied by each fragment entering the jaws too large to pass the throat, and thus avoiding crushing action because not requiring to be crushed, is one-half second, each such fragment will be exposed to five blows with one million foot pounds force, which may be judged to be sufficient for crushing any known ore or refractory rock.

Upon considering the operation of this crusher in respect to the rate of discharge of the crushed material therefrom relative to the rate of delivery thereto of the material to be crushed, it may be noted that the clearance for passage of the material substantially at the hub of the rotor as shown at D, in Figure 2 determines the limit of size to which the material must be reduced by crushing in order to pass through and be discharged. And it will be noted that this clearance is unvarying in the operation of the apparatus by reason of being at the plane of the pivots of the vibrating jaws and the axis of the rotor. And it will be noted that since the minimum opening of the jaws for entrance of the material at the upper end is the same as the minimum opening at the lower end for discharge, even if at any time all the material delivered to the apparatus at the upper end should be below said predetermined size, so that it would fall without delay to and through the zone of uniform clearance, the excess of clearance over the cross section of the stream of material passing at the discharge side of the apparatus even at the stage of closure of the jaws at the lower or discharge side, would be a very substantial amount, by reason of the gravity acceleration, making the discharge much more rapid than the gravity in flow. And in actual practice the proportion of the material not requiring to be crushed in order to pass the uniform clearance zone, would normally be a small fraction of the quantity of material delivered to the apparatus; and the material requiring crushing in order to pass that zone, would be detained, even in the case of the part most easily crushed and requiring least crushing to reduce it to size for passing, at least the length of time occupied in one complete oscillation of the jaws.

And in the detention of this material requiring crushing will blockade the passage at the point where said material is grasped by the jaws for crushing, and hold back the material following behind it for entrance between the jaws. So that in actual practice the crushed material will be moving at its discharge several times faster than at entrance, with the result that the passageway through the apparatus below the plane of the jaw pivots will be at all times at least seventy-five percent unoccupied; and the apparatus cannot become clogged except by the accidental entrance of an article too large to pass through the zone of unchanged clearance, and too hard to be crushed or broken by the apparatus; in which case the operator will adjust the jaws apart to get access to and remove the obstruction or permit it to fall through the passage made adequate by such adjustment as above described.

Furthermore, taking into consideration the high velocity of the rotor which will not only cause

the material after it is crushed to dimension for passing the zone of uniform clearance, to be impelled centrifugally against the jaws and further fragmentized, but also to be discharged at a 5 more rapid rate than above indicated due to gravity acceleration, it may be recognized that in actual experience, the discharge passageway below the plane of the jaw pivots will be much more largely unoccupied than as above indicated, so 10 that clogging, except by the accidental entrance of uncrushable substance, will be impossible.

I claim:

1. An apparatus for crushing refractory material comprising a frame structure; a pair of jaw members having each a recessed face, said jaw members being mounted in the frame structure with their recessed faces toward each other; a rotatable shaft journaled in the frame extending through both jaw members centrally with respect 20 to their recesses; a rotor carried by the shaft between the recessed jaw faces, said rotor being in diametric section symmetrically tapered narrowing outwardly radially from center to circumference, the jaw members being pivotally mounted 25 on the frame for oscillating longitudinally with respect to the shaft reciprocatingly toward and from each other, the pivot axes of the jaw members being parallel to each other and directly transverse to the shaft axis, and means for simultaneously rotating the shaft and oscillating the jaws.

2. An apparatus for crushing refractory material comprising a frame structure, a pair of crushing jaws having each a spherical concave face, said jaws being mounted in the frame structure with their concave faces toward each other; a rotatable shaft journaled on the frame extending through both jaws concentrically with respect to their spherical concavities; a rotor carried by the shaft between the concave jaw faces, said rotor being in diametric section symmetrically tapered narrowing from center to circumference, the jaw members being pivotally mounted on the frame for oscillating longitudinally with respect to the shaft reciprocatingly toward and from each other, the pivot axes of the jaw members being parallel to each other and directly transverse to the shaft axis, and means for concurrently rotating the shaft in oscillating the jaws.

3. The construction defined in claim 1, the means for oscillating the jaws comprising parts rotated by the shaft and operatively connected with the jaws respectively for oscillating the latter.

4. The construction defined in claim 1, the jaw-oscillating means comprising toggles connecting the jaws respectively with the frame structure at opposite sides of the rotor, and rotative elements carried by the shaft having toggle-actuating connections to the knee joints of the respective toggles.

5. An apparatus for crushing refractory material comprising a frame structure; a pair of crushing jaws and means carried by the frame structure by which they are individually horizontally pivoted medially of the extent of their opposed faces respectively; power-actuated means operatively connected with the jaws arranged to oscillate them respectively in opposite directions about their respective pivots, the jaws being arranged at the side thereof above the pivots for the introduction between them during their oscillation of material to be crushed, said power-actuated means comprising a power-driven rotatable shaft journaled on the frame

extending through the jaws at an axis transverse to the axes of the jaw pivots, and a rotor carried by the shaft between the jaws.

6. An apparatus for crushing refractory material comprising a frame structure; a pair of crushing jaws and means carried by the frame structure by which they are individually horizontally pivoted medially of the extent of their opposed faces respectively; power-actuated means operatively connected with the jaws arranged to oscillate them respectively in opposite directions about their respective pivots, the jaws being arranged at the side thereof above the pivots for the introduction between them during their oscillation of material to be crushed, the jaw-oscillating means comprising a pair of toggles operatively associated with each jaw with the two toggles of the pair connected at one end with the jaw at opposite sides of the jaw pivot on the frame and connected at the opposite end to the frame, and a power-driven shaft journaled in the frame and extending through both jaws transversely of the jaw pivots and between the two toggles of each pair, and means carried by the shaft at its said extent between the two toggles for operating oppositely on the two toggles simultaneously for flexing them respectively at their knee joints in opposite directions.

7. An apparatus for crushing refractory material comprising a frame structure; a pair of crushing jaws and means carried by the frame structure by which the jaws are individually horizontally pivoted medially of the extent of their opposed faces respectively; power-actuated means operatively connected with the jaws arranged to oscillate them respectively in opposite directions about their respective pivots, the jaws being arranged at the side thereof above the pivots for the introduction between them during their oscillation of material to be crushed, the jaw-oscillating means comprising a pair of toggles operatively associated with each jaw with the two toggles of the pair connected at one end with the jaw at opposite sides of the jaw pivot on the frame and connected at the opposite end to the frame, and a power-driven shaft journaled in the frame and extending through both jaws transversely of the jaw pivots and between the two toggles of each pair, an eccentric carried by the shaft in the transaxial plane of the knee joints of the toggles of each pair and cooperating with each eccentric for reciprocation thereby transversely of the shaft, an eccentric-encompassing element and links therefrom connected with the toggle at the knee joint of the latter, the parts being dimensioned for holding either toggle of the pair at straightened position when the other toggle of the pair is at the position of greatest flexure.

8. An apparatus for crushing refractory material comprising a frame structure, a pair of crushing jaws and means by which they are mounted in the frame facing each other, at least one of said jaws being pivoted horizontally at a medial point in its vertical extent opposite the other jaw, to render it vibratable toward and from the other; power-actuated means comprising two toggles connected to the pivoted jaw respectively above and below the jaw pivot, the connection of at least the toggle which is connected above said jaw pivot being relatively remote from said pivot; a power shaft journaled horizontally in the frame transversely of the jaw pivot; a part interposed in the journal bear-

- ing of the shaft and mounted therein for sliding vertically, said part having a vertically elongated aperture for the shaft wider than the shaft's diameter; a collar mounted concentrically on the shaft having its outer diameter equal to the width of said elongated aperture, and links connecting said slidably mounted part with the pivots of the knee joints of the toggles respectively; whereby the rotation of the shaft causing vertical reciprocation of said slidably mounted part operates the toggles for oscillating the pivoted jaw about its pivot to cause the two areas respectively above and below the pivot axis to alternate with each other in movements toward the corresponding areas of the other jaw, and means for introducing the material to be crushed between the jaws at the upper side thereof.
9. An apparatus for crushing refractory material comprising a frame structure; a pair of crushing jaws and means carried by the frame structure by which they are individually horizontally pivoted medially of the extent of their opposed faces respectively; power-actuated means operatively connected with the jaws arranged to oscillate them respectively in opposite directions about their respective pivots, the jaws being arranged at the side thereof above the pivots for the introduction between them during their oscillation of material to be crushed, the means for actuating the jaws for oscillation about their said medial pivots comprising in respect to each jaw a pair of toggles connected each at one end to the jaw, one remotely above and the other equally remotely below the pivot, and at the opposite end connected to the frame, and a shaft journaled in the frame extending between the two toggles with its axis transverse to the axis of the jaw pivot, and an eccentric cam element carried by said shaft substantially in the plane transverse to the shaft in which the knee joints of the toggles are located, and connection operated by said cam element to the knee pivots of the toggles for straightening and flexing each toggle in each revolution of the cam, the cam being symmetrically formed for actuating each toggle in direction for straightening simultaneously with the actuation of the other toggle for flexing; whereby the toggles operate for oscillating the jaws respectively about their pivots in opposite directions in each revolution of the shaft.
10. An apparatus for crushing refractory material comprising a frame structure; a pair of crushing jaws and means carried by the frame structure by which they are individually horizontally pivoted medially of the extent of their opposed faces respectively; power-actuated means operatively connected with the jaws arranged to oscillate them respectively in opposite directions about their respective pivots, the jaws being arranged at the side thereof above the pivots for the introduction between them during their oscillation of material to be crushed, the means for actuating the jaws for oscillation about their said medial pivots comprising in respect to each jaw a pair of toggles connected each at one end to the jaw, one remotely above and the other equally remotely below the pivot, and at the opposite end connected to the frame, and a shaft journaled in the frame extending between the two toggles with its axis transverse to the axis of the jaw pivot, an eccentric cam and encompassing ring carried by the shaft with links connecting the ring at opposite sides of the shaft to the knee joint

pivots of the opposite toggles respectively, whereby each revolution of the shaft causes the eccentric cam to straighten one toggle and simultaneously flex the other, and as to each toggle, to alternate straightening and flexing in each revolution.

11. The construction defined in claim 8 having both jaws pivoted horizontally and vibrated as described in claim 8, the power shaft extending through the jaws, and a rotor mounted on and rotated by the shaft between the jaws, the jaws being spaced apart from each other sufficiently to accommodate the rotor without contact of the jaws at their nearest approach to each other in their oscillation.

12. An apparatus for crushing refractory material comprising a frame structure; a pair of jaw members mounted facing each other and having their opposed faces recessed at equal directly opposed areas; a rotatable shaft journaled in the frame and extending through both jaws, said rotor being in diametric section symmetrically tapering widening inwardly from circumference toward the center correspondingly to the depth of the recesses of the opposed faces of the jaws, the jaw members being pivotally mounted on the frame for oscillating longitudinally with respect to the shaft reciprocatingly toward and from each other, the pivot axes of the jaw members being parallel to each other and directly transverse to the shaft axis and means for simultaneously rotating the shaft and oscillating the jaws, the jaw members having each at the upper side a semi-circular outwardly flaring flange, the two flanges being mated to each other for forming when the jaws are closed together a tapering funnel mouth leading to the cavity formed by the combined recesses of the two jaws, said flaring flanges being furnished with horizontally projecting flanges at opposite sides for spanning the gap between the funnel-forming flanges when the jaw members are adjusted for spacing them apart from each other.

13. The construction defined in claim 12, the funnel-forming flanges being formed on their inner surfaces with V-shaped corrugations presenting upwardly facing flat shoulders for lodgment of the fragments of a refractory material to retard their descent into the jaws and facilitating the crushing of said fragments in the oscillatory closing together of the jaws at the upper side.

14. The construction defined in claim 1, the rotor having in each of its opposite faces toward the jaws respectively a circular series of shallow pockets each forming a shoulder facing away from the axis of revolution of the rotor and lateral radially extending shoulders for engagement and actuation rotatively with respect to the shaft of fragments of the material delivered to the apparatus for crushing.

15. An apparatus for crushing refractory material comprising a frame structure; a pair of crushing jaws and means carried by the frame structure by which they are individually horizontally pivoted medially of the extent of their opposed faces respectively; power-actuated means operatively connected with the jaws arranged to oscillate them respectively in opposite directions about their respective pivots, the jaws being arranged at the side thereof above the pivots for the introduction between them during their oscillation of material to be crushed, the frame structure comprising a main frame

arranged to support power-actuated means, said power-actuated means comprising a power driven shaft journalled on the main frame; two frame members constituting respectively the immediate supports on which the jaws respectively are pivoted, said frame members being mounted slidingly on the main frame, and means operable at will for adjusting them on the main frame to adjust the jaws in respect to the distance between their co-operating faces.

16. An apparatus for crushing refractory material comprising a frame structure; a pair of crushing jaws carried by the frame structure by which they are individually horizontally pivoted medially of the extent of their opposed faces respectively, jaw-oscillating means comprising a pair of toggles operatively associated with each jaw with the two toggles of the pair connected at one end with the jaw at opposite sides of the jaw pivot on the frame, and connected at the opposite end to the frame, and a power-driven

shaft journalled in the frame and extending through both jaws transversely of the jaw pivots and between the two toggles of each pair, and means carried by the shaft at its said extent between the two toggles for operating oppositely on the two toggles simultaneously for flexing them respectively at their knee joints in opposite directions, the jaws having each at the upper end an extension, said extensions constituting an inleading mouth piece for receiving material to be crushed arranged for crushing the material introduced at said mouth piece in the oscillation of the jaws, and a third toggle associated with each jaw and with the part of the toggles pertaining thereto connected at one end to the jaw toward the upper end of said extension and at the other end to the frame, and having the pivot of the knee joint link-connected with the pivot of the knee joint of the upper toggle of the pair.

ROBERT LINN. 20
